UNITED STATES PATENT OFFICE.

JAMES H. REED, OF SWAMPSCOTT, MASSACHUSETTS.

TACK-MAKING MACHINE.

1,272,097.

Specification of Letters Patent.

Patented July 9, 1918.

Application filed October 18, 1917, Serial No. 197,367.

To all whom it may concern:

Be it known that I, JAMES H. REED, a citizen of the United States, residing at Swampscott, county of Essex, State of Massachusetts, have invented a certain new and useful Improvement in Tack-Making Machines, of which the following is a specification, reference being had therein to the accompanying drawings.

10 My invention has for its object a new and improved machine for the manufacture of tacks from strips of sheet metal. The tacks made by my improved machine are the ordinary tack employed in the manufacture of shoes, in upholstery and for like purposes and consists of a shank having a cut point, a round head at the other end, the shank itself being substantially cylindrical or slightly frusto-conical adjacent the head. A machine embodying my invention comprises essentially mechanism for advancing a strip of material step by step to a punch; a punch which cuts suitable wedge shape slugs or blanks from the end of the strip; the points and butts alternating in position; a pair of dies which round the portion of the blank adjacent the point where the head is formed, and suitable mechanism for forming the head on the tack. The position of the punch is changed after each stroke thereby cutting blanks the points and butts of which alternate in position. This construction does away with the complicated machinery heretofore employed in tack making machines by which the strip from which the blanks are cut is turned bottom-side up after each stroke of the punch. In the machine embodying my invention, the punch delivers the slug directly to the die which forms the rounded portion of the shank and by which in coöperation with a head forming hammer forms the head of the tack. The die is so constructed that the head is always formed on the butt of the slug there being two head forming hammers one on each side of the machine. The dies and head forming hammers operate to produce a tack, the head of which is round and true and does not need to be trimmed so that my machine does away entirely with the expensive operation of trimming the heads of the tacks after they have been formed for which purpose an expensive, delicate and complicated machine has heretofore been employed.

The machine embodying my invention is

simple and inexpensive and capable of being run at high speed. It forms a finished tack directly from the strip of material at a minimum of expense.

The invention will be fully understood when taken in connection with the following description and the accompanying drawings and the novel features thereof will be pointed out and clearly defined in the claims at the close of this specification.

In the drawings, Figure 1 is an elevation partly in section of a machine embodying my invention.

Fig. 2 is a section on line 2—2 of Fig. 1. 70

Fig. 3 is a section on line 3—3 of Fig. 2.

Figs. 4 and 5 are sections of the central portion of the machine showing the working instrumentalities in successive positions.

Fig. 6 is a detail showing the head forming hammers in another position.

Fig. 7 is a plan view showing in detail the formation of the head of the tack by the coöperating dies and head forming hammer.

Fig. 8 is a section on line 8—8 of Fig. 1. 80

Fig. 9 is an enlarged view of the face of the die 50.

Fig. 10 is a plan view of the strip showing how successive slugs or blanks are cut therefrom.

Fig. 11 is a plan view of a slug or blank cut by the punch and from which a tack is to be made.

Fig. 12 is a view of the finished tack on an enlarged scale.

Referring now to the drawings and particularly to Fig. 12, there is shown therein a tack such as is made by the machine described herein. This tack consists of a cut point *a*, a substantially cylindrical or slightly frusto-conical portion *b* and a circular or disk shaped head *c* located symmetrically with relation to the longitudinal axis of the tack. As will be understood, the shape of the tack produced can be varied as desired by changing the matrices in the dies. The blank or slug from which this tack is made is shown at *d* in Fig. 11 and is wedge shaped having a sharp point and a relatively wide butt. At *e* in Fig. 10 is shown a portion of a strip of material from which the blanks *d* are cut. Four successive cuts are indicated by dotted lines *f* in Fig. 10. It will be seen that they are at an angle to the sides of the strip so that the points and butts of the slugs alternate in position.

At 11 is shown the bed plate or table of

the machine. Beneath this table is supported a main shaft 12 having thereon suitable cams and gears to produce the requisite movements of the working parts of the machine. At *e* is shown the strip of material which is fed by a suitable guide 14 to the punch 15. The feeding of the strip step by step for exactly the right distance is accomplished by a roll feed consisting of a pair of knurled feed rolls 16 and 17 mounted respectively above and below the strip *e*. Said feed rolls are geared together by gears one of which 18 is shown in Fig. 2. The axle 19 of the lower roll is provided with an arm 20 loosely mounted thereon and containing a roll 21 and spring 22 which together with the hub 27 constitutes a roll clutch so that the oscillating movement of the arm 20 gives the feed rolls a step by step motion in one direction only. The arm 20 is formed in two parts and is adjustable in length by means of the bolt 23. This adjustment varies the length of the feed of the strip and consequently the width of the slug which will be produced. The arm 20 is oscillated by a link 24 on one end of which is mounted a roll 25 which moves in a slot 26 in a cam on the main shaft 12 of the machine. The upper feed roll 16 is mounted in an arm 28 which is downwardly pressed by a spring 29 so that the feed rolls will exert the necessary pressure on the strip *e* to feed it forward accurately.

The punch 15 is mounted at the lower end of a square slide 30 itself carried in an oscillating frame 31. This oscillating frame 31 has a cylindrical boss or bearing *g* formed on the bottom which is received within a corresponding circular hole in the bed 11 of the machine. The frame 31 also comprises a pair of side extensions *h* which as will be hereinafter described carry the head forming hammers and a rearward extension *i* by means of which the frame 31 is oscillated. The oscillation of the frame is produced by a cam 32 which is cut or formed in such a manner that the oscillating frame will remain substantially stationary at the end of each half oscillation to give the punch 15 an opportunity to perform its function while the oscillating frame 31 is stationary. The upper end of the square slide 30 is cylindrical in shape as shown at 34 with a groove 35 therein. The cylindrical end 34 extends up into a hole in the under side of a head 36 and is secured thereto by pins 37 (see Figs. 1 and 3) which lie tangentially in the groove 35. This construction permits the square shaft 30 carrying the punch 15 to oscillate with the oscillating frame 31 while the head 36 which actuates the punch remains stationary. The head 36 contains a cam groove 38 in which moves a roll 39 located eccentrically on a shaft 40 carried in a stationary bracket 41 on the upper part

of the machine. The rear end of the shaft 40 is provided with a beveled gear 42 meshing with a large bevel gear 43 on a vertical shaft 44 the lower end of which is provided with a bevel gear 45 engaged by another bevel gear 46 on the main shaft 12 of the machine.

The punch 15 cooperates with the edge of a hardened plate 47 on which the strip rests so that the punch and plate act as a shear in the cutting of the slugs from the end of the strip. As the punch and plate 47 are both carried in the oscillating frame, it will be seen that they maintain their proper relative positions with regard to each other even though they oscillate with the frame 31 with relation to the longitudinal axis of the strip.

Directly beneath the strip *e*, is located a finger 48 having in the top thereof a notch *j* for engagement with the slug. The finger 48 is on the upper end of a rod 90 guided in a hole in the boss *g* on the frame of the machine. The lower end of the rod 90 is L-shaped and is formed into a member 50 located in one end of a lever 52 pivoted at 53 to a depending bracket 54 on the under side of the table 11. The rear end of the lever 52 carries a cam roll 51 located in a cam slot 55 in the side of a plate cam 56. This plate cam 56 is mounted on the main shaft 12 of the machine and the cam groove is so devised that the finger 48 will be in its highest position just before the bottom of the stroke of the punch 15 and the punch will push the slug down into the notch *j* in the upper end of the finger 48. The cam is also arranged so that thereafter the punch and finger will move downward in unison carrying the slug between them to a predetermined point. The successive positions of the punch 15 and finger 48 will be clearly seen from Figs. 1, 4 and 5.

The dies by which the slug is formed into a tack consist of a reciprocating die 50 and a stationary die 51.

In the proximate vertical faces of these two dies, there are formed suitable matrices for the formation of the shank and head of the tack. The form of one of these matrices may be seen in Fig. 9. It consists of a semi-cylindrical portion *l* and an enlarged semi-cylindrical portion *m* on one end and *n* on the other end in which the disk shaped heads of successive tacks are formed. It will be understood of course that the heads of successive tacks are formed alternately by the matrices *l* and *m* respectively. Or to state this matter in another way, a tack is first formed with its head at the right as shown in Fig. 9 and the next tack is formed with its head at the left.

In the vertical face of the movable die member 50, is located a spring pin 57 having a notched end to engage the slug. Be-

hind the pin is a spring 58 which allows the pin to yield and be pushed back into the pocket in the movable die 50. The function of the spring pin 57 is to seize the slug when 5 it has been moved down vertically to a point on a level with the matrices (see Fig. 4) and to push it into the matrix in the stationary die 51 holding it there until the punch 15 is lifted and the finger 48 has been with- 10 drawn so that the two dies can come together. The movable die 50 is actuated by a toggle joint 60 pivoted at one end to the movable die and at the other end to the oscillating frame as shown at 61. The toggle joint is straightened by a vertical rod 62 carrying on its upper end a cam roll 63 located in a cam groove in the face of a plate cam 64. The minute amount of play necessary owing to the fact that the up- 15 per end of the cam rod 62 coöperates with the cam 64 on the stationary bracket 41 while the lower end coöperates with the toggle joint 60 carried on the oscillating frame 31 is not sufficient to interfere with 20 the operation of the parts. The toggle joint 60 pushes the movable die 50 against the face of the stationary die 51 at the proper time with sufficient force to form the cylindrical portion on the shank of the 25 tack. The dies remain in closed position 30 for a sufficient length of time to permit the inward movement of one or the other of the head forming hammers by which the end of the shank is compressed into the portion 7 and *m* of the matrix to form the disk shaped 35 head. The head forming hammers will clearly be seen at 65 and 66 in Figs. 2, 3, 6 and 7. Each head forming hammer has a cylindrical projection *n* of the size of the 40 head of the tack. The other end of the hammer is connected to a toggle 67 one end of which is connected at 68 to lugs in the frame of the machine. The toggle is actuated by a link 69 the lower end of which is 45 connected by a universal joint 70 to a pivoted lever 71. This lever 71 carries on its rear end a cam roll 72 operating in a cam slot 73 in the face of a plate cam 74. Both hammers 65 and 66 have similar operating 50 mechanism and therefore only one of them has been described, the same numbers applying to similar parts of both mechanisms. 55 The two cams 74 which operate the hammers 65 and 66 are so set on the main shaft 12 of the machine that the hammers are operated alternately, that is to say, while one hammer is in forming the head of a tack, the other hammer is withdrawn as far as possible (see Fig. 7) so that it will not interfere with the point of the tack which is 60 then being formed.

In the operation of my machine, the strip of sheet material which may, if preferred, be in the form of a coil, is fed step by step 65 between the punch and block. The punch

descends, cutting off a triangular slug which is deposited by the punch in the notch in the upper end of the finger 48. Thereafter, the punch 15 and the finger 48 descends together, carrying the slug with them, until 70 a point opposite the matrix in the die 51 is reached. The die 50 then advances until the spring finger 57 strikes the slug and pushes it into the matrix in the die 51 holding it there. The punch and finger then 75 withdraw and a further movement of the die 50 compresses the tack into the cylindrical portion of the matrix. When the dies 50 and 51 are fully closed, one of the head forming hammers 65 or 66 moves inwardly 80 and in coöperation with the enlarged portion of the matrix, forms the head of the tack, the tack being held meanwhile by the pressure exerted by the die 50. The oscillating frame 31 then swings about the boss 85 *g*, thus changing the position of the punch 15 and block 47 relatively to the end of the strip so that on the next downward movement of the punch, a slug will be cut, the point of which lies in the opposite direction 90 from the preceding slug. The tack is formed from this slug in the same manner as already described, except that the formation of the head is accomplished by the other of the head forming hammers 65 and 66. 95

What I claim is:

1. In a machine of the character described, a frame, a punch and block oscillatable relatively to said frame, means for oscillating the punch and block, means carried by the 100 frame to reciprocate the punch there being a loose connection between the punch and its reciprocating means to permit the said oscillation.
2. In a machine of the character described, 105 a stationary frame, an oscillatable frame, a punch and block and head forming mechanism mounted in said oscillatable frame, stationary strip feeding mechanism, means for reciprocating the punch, and means for oscillating said oscillatable frame between successive reciprocations of the punch.
3. In a machine of the character described, 110 a stationary frame having an overhanging bracket, an oscillatable frame supported on said stationary frame, a punch and block mounted on said oscillatable frame, actuating means for the said punch in the bracket of the said stationary frame, oscillating means for the oscillatable frame, there being a loose connection between said punch and the reciprocating means therefor to permit said oscillation.
4. In a machine of the character described, 115 strip feeding mechanism, a reciprocating punch and tack forming dies movable relatively to each other, and so located as to permit the punch to deposit a slug in the said dies.
5. In a machine of the character described, 120 125

the combination with a shearing punch and block, tack forming dies, means for moving said dies relatively to each other, and a finger coöperating with the said punch to deposit a slug cut by the said punch between the said dies.

6. In a machine of the character described, the combination with a shearing punch and block, a pair of tack forming dies, movable 10 toward and away from each other, and a spring finger in the face of one of said dies to hold a slug cut by the punch in proper position relatively to the other die.

7. In a machine of the character described, 15 the combination with a shearing punch and block, step by step strip feeding mechanism, tack forming mechanism including dies and a head forming hammer reciprocating lengthwise of the tack to be formed, and 20 means for oscillating the punch and block and the tack forming mechanism as a whole relatively to the feeding mechanism between successive strokes of the punch.

8. In a machine of the character described, 25 a stationary frame, an oscillatable frame mounted on said stationary frame, a punch and block carried by said oscillatable frame, tack forming dies and head forming hammers mounted on said oscillatable frame, stationary strip feeding mechanism, means for reciprocating said punch, and means for oscillating said oscillatable frame between reciprocations of the punch.

9. In a machine of the character described, 30 step by step strip feeding mechanism, a reciprocating punch and block, tack forming

dies, one of which is capable of reciprocation relatively to the other, the matrices of which are constructed to permit the formation of successive tacks with the points in opposite 40 directions, means for reciprocating the punch, and means for oscillating the punch between successive reciprocations whereby the punch will form successive slugs, the points of which alternate in direction and 45 will deliver said slugs to the tack forming dies, said dies being in line with the punch so that the dies will receive the slugs directly from the punch.

10. In a machine of the character described 50 and in combination a die formed in two parts longitudinally of the tack to be formed, said parts together containing a double ended matrix, means for reciprocating one part of the matrix relatively to the other, and alternately acting head forming hammers on opposite sides of said die whereby alternate tacks will be formed with their heads in opposite directions.

11. In a machine of the character described 55 strip feeding mechanism, a reciprocating punch, a pair of tack forming dies having a matrix for the formation of a tack, said tack forming dies being located in line with the reciprocating punch, a finger reciprocating in line with the punch to assist the punch to deposit the slug in the said dies, and a spring finger in the face of one of said dies to hold a slug cut by the punch in proper position relatively to the other die. 60 65

In testimony whereof I affix my signature.

JAMES H. REED.
